(57) **CLAIM**

The ornamental design for an illumination device, as shown and described.

DESCRIPTION

FIG. 1 is a front perspective view of a first embodiment of an illumination device showing my new design.

FIG. 2 is a front view thereof.

FIG. 3 is a left side view thereof.

FIG. 4 is a right side view thereof.

FIG. 5 is a top plan view thereof.

FIG. 6 is a bottom plan view thereof.

FIG. 7 is a front perspective view of a second embodiment of an illumination device showing my new design.

FIG. 8 is a front view thereof.

FIG. 9 is a rear view thereof.

FIG. 10 is a left side view thereof.

FIG. 11 is a right side view thereof.

FIG. 12 is a top plan view thereof; and,

FIG. 13 is a bottom plan view thereof.

The broken lines in FIGS. 1-13 are intended to illustrate environmental structure for the claimed design and form no part of the claimed design.
